US0D1040610S

(12) **United States Design Patent** (10) Patent No.: **US D1,040,610 S**
(45) Date of Patent: ** Sep. 3, 2024

(54) **PART OF NON-ELECTRIC COFFEE GRINDER**

(71) Applicant: **Bernd Braune**, Unterhaching (DE)

(72) Inventors: **Bernd Braune**, Unterhaching (DE);
Raphael Braune, Unterhaching (DE)

(**) Term: **15 Years**

(21) Appl. No.: **35/516,954**

(22) Filed: **Jun. 10, 2022**

(80) **Hague Agreement Data**

Int. Filing Date: **Jun. 10, 2022**

Int. Reg. No.: **DM/222459**

Int. Reg. Date: **Jun. 10, 2022**

Int. Reg. Pub. Date: **Apr. 28, 2023**

(30) **Foreign Application Priority Data**

Dec. 22, 2021 (EM) 008802748-0001

(57) **CLAIM**

The ornamental design for a part of non-electric coffee grinder, as shown and described.

DESCRIPTION

1. Part of non-electric coffee grinder

1.1 : Perspective

1.2 : Top

1.3 : Bottom

1.4 : Right

1.5 : Left

1.6 : Front

1.7 : Back

Characteristic feature is the overall shape of the industrial design of the grinder.

(Continued)

The broken lines and non-shaded area between the broken lines illustrate a portion of the article that form no part of the claimed design.
